VALVE FOR STEAM ENGINES.

APPLICATION FILED SEPT. 20, 1904.

2 SHEETS—SHEET 2.

UNITED STATES PATENT OFFICE.

CHARLES EDWARD LOWE, OF EUFAULA, INDIAN TERRITORY.

VALVE FOR STEAM-ENGINES.

SPECIFICATION forming part of Letters Patent No. 779,226, dated January 3, 1905.

Application filed September 20, 1904. Serial No. 225,207.

To all whom it may concern:

Be it known that I, CHARLES EDWARD LOWE, a citizen of the United States, residing at Eufaula, Creek Nation, Indian Territory, 5 have invented a new and useful Improvement in Valves for Steam-Engines, of which the following is a specification.

My invention relates to improvements in valves for steam-engines, its object being to 10 provide a valve which will work with less friction than the ordinary slide-valve by doing away with stuffing-boxes and packing-glands for the valve-rod.

My invention consists in certain novel features of construction, arrangement, and operation of parts, as will be hereinafter fully described, and pointed out in the claims.

In the drawings, Figure 1 is a perspective view of an engine embodying my improvements. Fig. 2 is a plan view of the interior of the steam-chest, showing the valve-seat. Fig. 3 is a detached perspective view of the slide-valve turned to show the rear side thereof. Fig. 4 is a vertical section taken through 25 the center of the steam-chest. Fig. 5 is a vertical section taken on line xx of Fig. 2. Fig. 6 is a similar section taken on line yy of Fig. 2. Fig. 7 is a transverse central vertical section of the steam-chest, and Fig. 8 is a detail 30 section of the guide and clamping screws.

As shown in Fig. 1, 1 represents cylinder of an engine, and 2 the steam-chest. Said chest is located at one side of the cylinder and is divided into an upper and lower chamber 35 by the partition 3. The steam-chest has a removable cover 4 and a removable side door 5. The partition 3 has an elongated longitudinal slot 6 in its center and at each end has the inlet-ports 7 7 and exhaust-ports 8 8. The 40 upper edge of slot is surrounded by a flange 9, the purpose of said flange being to prevent any water that might collect in the upper chamber of the steam-chest from dripping into the lower chamber. 10 10 represent 45 the live-steam ports leading from the steam-chest to the cylinder, and 11 11 indicate the exhaust-ports leading from the steam-chest to the outlet-pipe 12, which leads to the open air. The upper face of the partition 3, which 50 forms the valve-seat, is provided with a fac-

ing-strip 13, provided with the necessary openings to register with the ports in said partition. A vertical strip 14 is secured to the rear wall of the upper chamber, against which the valve will bear.

55

15 represents the slide-valve, comprising a central portion and two dome-like parts 16 at each end, within which domes are the exhaust-cups 17. Depending from the central part of the valve is the stem 18, secured thereto by being screwed to it or made rigid with the valve in any other suitable manner. The lower face of the valve has secured to it the bearing strip or plate 19, provided with suitable openings for the exhaust-cups and for 60 the passage of the stem 18. The rear face of the valve is provided at each end with the lugs 20 20, which bear against the strips on the rear wall of the upper chamber of the steam-chest. The guide-strip 21 fits under a 65 ledge 22, projecting from the front wall of the upper chamber of the valve-chest, and bears against the front face of the slide-valve. Said ledge has near each end a depression and a threaded opening through the 70 ledge within each depression. A set-screw 23 is fitted to each opening in each depression and bears against the upper face of the guide-strip 21 to hold it firmly in position when adjusted laterally, which may be done by 75 passing a thin strip through the slot 24, extending through the ledge 22, as shown in Figs. 2 and 7.

80

To the lower end of the stem 18 is secured by a suitable pivotal bearing the end of the 85 valve-rod 25, which extends from the valve-stem to the eccentric in line with the ordinary piston-rod. The upper part of the valve-rod at the end where it is connected to the valve stem or shank 18 is provided with a long narrow cup 26, which receives the oil from the lubricator and lubricates the bearing through an opening. The oil is received from the lubricator 27 on the top of the steam-chest through the small tube 28, which extends 90 downwardly and is suitably bent to pass in between the door 5, which is provided with a groove 5^a to receive said tube 28 and permit the door to make a tight closure. Said door 95 is made heavier at the bottom, as indicated 100

in Figs. 6 and 7, to keep it in place and is provided with the flange extensions, the lower one fitting within the lugs 10^a, which aid in retaining the door in position. The door is provided with a suitable handle to remove and replace the same.

Extending from the lower chamber of the steam-chest is an outlet-pipe 29 to carry off any water that may escape over the flanges 10 of the slot 6.

Steam is admitted to the upper chamber of the steam-chest through pipe 30 and passing through port 7 enters the cylinder at the right hand and drives the piston toward the left hand of the cylinder, the exhaust-steam passing through the port 7 at the left-hand end to the exhaust-cup 17 at that end and thence through exhaust-port 8 to the open air. The valve which moves one-fourth ahead of the piston then moves to the right in covering port 7, when live steam will be admitted to left-hand end of the cylinder and drive the piston to the right. These alternate movements are kept up as long as the engine is 25 running.

It will be noted that all of the bearing-faces are steam-tight and that I dispense with a valve-rod secured to one end of the rod and passing through packing or stuffing boxes in 30 the end of the valve-chest. The valve will be held to its seat by live steam against the flange surrounding the slot 6. The parts can be readily gotten at for repair or removal. It will also be noted that the exhaust takes 35 place at each end of the valve and at each end of the steam-chest instead of at the center, as is usually the practice.

Having thus described my invention, what I claim as new, and desire to secure by Letters 40 Patent, is—

1. The combination with a cylinder and a steam-chest divided into two chambers by a slotted partition forming a valve-seat having steam and exhaust ports at its ends, of a slide-valve located in one chamber and provided at 45 each end with exhaust-cups, a valve-stem extending through said slotted valve-seat, and means for connecting said valve-stem with the eccentric of an engine.

50 2. The combination with a cylinder and a steam-chest, said chest divided into two chambers by a slotted partition forming the valve-

seat, said valve-seat having inlet and exhaust ports at each end, of a slide-valve seated on said valve-seat and having at each end exhaust-cups, and provided at its center with a valve-stem extending through the slotted valve-seat, a guide-strip located at one side of the valve-chamber and adapted to bear against one face of the slide-valve, means for adjusting said 55 guide-strip and securing it in its adjusted position, and means for operatively connecting the valve-stem with the eccentric of an engine.

3. The combination with a cylinder and a steam-chest, said chest divided into two chambers by a centrally-slotted partition forming a valve-seat, said valve-seat having an inlet and an exhaust port at each end, facing-strips secured to the working face of the valve-seat and a flange surrounding the slot in the center of the valve-seat, of a slide-valve provided with facing-strips on its working face and having an exhaust cup or dome at each end, a valve-stem extending from the center of the valve through the slotted valve-seat, and an 65 eccentric-rod pivotally connected with said 70 valve-stem.

4. The combination with a cylinder and steam-chest divided into two compartments by a partition provided with an elongated central slot, said partition forming the valve-seat and having an inlet and exhaust port at each 80 end, of a slide-valve having an exhaust cup or dome at each end and a valve-stem projecting 85 therefrom through the slot in the partition, an eccentric-rod pivotally connected at one end with said valve-stem, and means for lubricating such pivotal connection.

5. The combination with a cylinder and steam-chest divided into two chambers by a 90 centrally-slotted partition forming a valve-seat, said valve-seat having an inlet and an exhaust port at each end and passages leading from said ports to the cylinder and open air respectively, of a slide-valve fitted to slide on 95 said valve-seat, it having at each end an exhaust cup or dome, a stem projecting from said valve through the centrally-slotted partition, and an eccentric-rod pivotally connected to said valve-stem.

CHARLES EDWARD LOWE.
